WILLIAM C. GOODWIN, OF HAMDEN, CONNECTICUT,

Design No. 4,370, dated September 27, 1870.

DESIGN FOR THE FIGURE OF A MECHANICAL TOY.

The Schedule referred to in these Letters Patent and making part of the same.

To all whom it may concern:

Be it known that I, WILLIAM C. GOODWIN, of Hamden, in the county of New Haven and State of Connecticut, have invented a new Design for the Figure of Mechanical Toys; and I do hereby declare the following, when taken in connection with the accompanying drawing, and the letters of reference marked thereon, to be a full, clear, and exact description of the same, and which said drawing constitutes part of this specification, and represents a front view.

This invention relates to a design for toys, such as are applied to heating apparatus to receive a power to operate them from the rising heat, and consists in a figure representing a person washing.

The body of the figure is divided at the hips; the upper portion attached to the shaft A, so that, by the revolution of the shaft, the body is drawn forward and back, as denoted in broken lines. The arms, pivoted to the body, appear to be rubbing in the tub.

I claim as my invention—

The design for a figure for mechanical toys, as described and shown.

W. C. GOODWIN.
